Primary Examiner — Jonathan J Han*Assistant Examiner* — Molly K. Orzechowski(74) *Attorney, Agent, or Firm* — Banner & Witcoff, Ltd.**(57) CLAIM**

The ornamental design for a shoe, as shown and described.

DESCRIPTION

FIG. 1 is a side photographic view of a shoe showing our new design; and,

FIG. 2 is an enlarged view of the design as shown in FIG. 1 with surrounding environment removed for clarity purposes.

The broken line rectangle and lighter grey area within it form no part of the claimed design. The broken lines immediately adjacent to the sides of the photographic area define the bounds of the claimed design and form no part thereof. The remainder of the shoe shown in a lighter grey photographic depiction forms no part of the claimed design.
